[57] CLAIM

The ornamental design for an acetabular cup assembly prosthesis, as shown and described.

DESCRIPTION

FIG. 1 is a front elevational view of an acetabular cup assembly prosthesis showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a right side elevational view thereof with the assembly rotated 45° in a counterclockwise direction;

FIG. 7 is a sectional view taken along line 7—7 of FIG. 2;

FIG. 8 is a front elevational view of a modified acetabular cup assembly prosthesis showing my new design;

FIG. 9 is a top plan view of the prosthesis shown in FIG. 8;

FIG. 10 is a bottom plan view of the prosthesis shown in FIG. 8;

FIG. 11 is a right side elevational view of the prosthesis shown in FIG. 8;

FIG. 12 is a front elevational view of a further modified acetabular cup assembly prosthesis showing my new design;

FIG. 13 is a top plan view of the prosthesis shown in FIG. 12;

FIG. 14 is a bottom plan view of the prosthesis shown in FIG. 12;

FIG. 15 is a right side elevational view of the prosthesis shown in FIG. 12; and

FIG. 16 is a rear elevational view of the prosthesis shown in FIG. 12.
